TAPE DISPENSER

Clyde W. Double, Crafton, Pa.

Application July 21, 1950, Serial No. 175,055

1. Claim. (Cl. 164—84.5)

1 This invention relates generally to dispensers and more particularly to a dispensing device for adhesive tapes which are available in rolls.

The tape-cutting dispenser comprising this invention is of the character that is not attached to the roll but may be readily carried with the roll by the adhesive of the tape and dispense the tape therefrom while the roll is being held in the hand.

Dispensers adapted to be attached to a free roll of tape and having an underguide or shoe that engages in the hole inside of the roll require the shoe to be adjusted or taken up as the tape on the roll is reduced in thickness upon the dispensing of tape therefrom. The tape dispenser comprising this invention is not required to have any shoe or extension engaging the inner opening of the roll, such as disclosed in patents, and the dispenser comprising this invention is an improvement over the structures shown in these patents.

The principal object of this invention is the provision of an adhesive tape dispenser having a surface against which the adhesive portion of the tape and extending from the roll lies in contact for the purpose of supporting and holding the dispenser to the roll. The dispenser, as comprising this invention, may be applied to rolls of different diameters and of different widths and will function properly, whereas in the prior art the tape dispensers are required to be fitted to the particular size of tape.

Another object of this invention is the provision of a tape dispenser comprising a sliding shoe which engages the perimeter of the adhesive roll and is thereby guided to slide therewith. This dispenser is provided with spaced upward extensions for supporting the free end of the tape, as it extends from the surface of the roll and bridges from one extension to another thereby permitting the tape to be readily lifted and dispensed. This is an extremely important object of this invention.

Another object of this invention is the provision of spaced bearing means on the tape engaging shoe to engage the surface of the tape and maintain the dispenser in proper relative position so that the end thereof will not re-engage the surface of the roll when the adhesive tape is being dispensed, nor will it present a difficult problem in freeing the end of the tape to permit it to be withdrawn from the roll and dispensed in the length desired.

Other objects and advantages appear herein-after in the following description of claim.

2 The accompanying drawings show for the purpose of exemplification without limiting the invention or claim thereto a practical embodiment illustrating the principles of this invention wherein:

Fig. 1 is a sectional view of the tape dispenser comprising this invention as shown in engagement with the roll of tape.

Fig. 2 is a perspective view of the dispenser 10 as shown in Fig. 1.

Fig. 3 is a perspective view of a modified form of tape dispenser comprising this invention.

Fig. 4 is a perspective view of the structure as shown in Fig. 3 as applied to a roll of tape.

15 Referring to Figs. 1 and 2 of the drawings it will be noted that the tape dispenser 1 is applied to a large roll of transparent tape. The tape dispenser 1 is provided with the depending sides 2 and 3 that extend from the marginal side 20 edges of the sole 4 of the shoe. The sole is provided with two depending bearing members 5 and 6 which are struck from the surface of the sole member openings 7 and 8 therein. The lower end of the downwardly struck members provide bearing points that ride on the smooth surface of the tape roll indicated at 9. These bearing members may have rolled ends to permit them to easily ride over the tape. Intermediate of the bearing surfaces, the sole 4 is provided with an opening 10 formed by the oppositely disposed upward extension members 11 and 12. The extension member 12 is larger than the extension members 11. However, both extension members have arcuately curved surfaces extending in opposite directions from each other. A fore end of the shoe sole 4 is provided with an upward extension 13 that is preferably higher than the upward extension 12 and has a transverse cutting bar 14 on the forward edge thereof. The arcuate 25 surface of the upward extension 12 projects toward the upper end of the upward extension 13 and the free end of the tape, which is indicated by the dotted line at 15, extends upwardly from the surface of the tape roll through the opening 10 and in engagement with the arcuate 30 surface of the upward extension 12 and bridges the gap between the spaced upward extensions 12 and 13 and lies in engagement with the top abutment surface 16 of the upward extension 12 35 and 13 where any downward pressure may be exerted to tear it across the cutting bar 14.

40 When this very simple structure is applied to a roll of tape, it may be held by the thumb and forefinger on the roll and the loose end of the tape may be lifted upwardly from the abutment 45 50 55

surface 16 of the extension 13 and be freed of the arcuate surface on the upward extension 12. The tape may then be drawn substantially vertically through the opening 10 to any length desired. The smooth end of the tape may be turned rearwardly over the arcuate surface of the upper extension 11 and pulled so as to slide the roll of tape on the bearings of the shoe 1 as the tape is withdrawn from the roll, and, when it is desired to stop and cut the proper length of the tape, the tape extension is merely moved forward until its adhesive surface engages the arcuate surface 12 to lock the shoe to the roll. The tape then bridges over the gap between the extensions 12 and 13 and, when stretched and pulled down over the abutment 16, it is severed by the bar 14.

This structure is very simple and economical being stamped from a single piece of metal and needing no additional work thereto other than possibly painting or printing before stamping. However, if made from aluminum or stainless steel, a surface finish for the dispenser is not even necessary.

In the structures shown in Figs. 3 and 4 the shoe 20 is provided with the spaced abutment members 21 and 22 which are formed by curving the ends 23 and 24 inwardly between the sides 25 and 26 as shown in Fig. 4. The upper end of abutment 21 is provided with an arcuate surface 27 that extends toward the head 28 on the upper end of the abutment member 22. The head 28 is provided with the cutting bar indicated at 31. This structure has the same elements and operating characteristics as the aforementioned structure in that it is provided with spaced tape engaging and bearing surfaces and spaced extensions having abutment surfaces that function to bridge the end of the tape over the gap therebetween to permit the fingers to readily grasp the end of the tape and lift it from the surfaces. The only substantial difference between these structures is the fact that the structure, as shown in Figs. 3 and 4, is not provided with the openings 7 and 10 as shown in Fig. 1.

The dispenser of Figs. 3 and 4 is provided with the finger indentations 32 in the sides thereof which, when held between the thumb and forefinger, will permit the roll of tape to slide around in the hands when the free end of the tape is being drawn from the surface thereof, and closely adjacent the abutment 21 as indicated by the dotted line at 33.

Owing to the fact that each of the dispensers as disclosed in this application is provided with spaced bearings for engaging the smooth surface of the tape, a dispenser may support the tape

roll, which may be readily slid around while the roll is supported by the spaced bearings, and permitted to rotate in the hand while the free end of the tape is being withdrawn from the roll.

Another important feature of this invention, that is common to both of these dispenser structures, is found in the upwardly spaced abutments which permit the adhesive surface of the free end of the tape to engage the surface of the first abutment to hold the dispenser to the roll of tape when not in use and also to provide a bridge which is readily lifted by the fingers without disengaging the adhesive surface of the tape end from the arcuate surface of the first abutment. This permits one to handle and quickly draw sections of the tape from the roll without dropping either the roll, or the dispenser, or necessitate the carrying of a bulky dispenser.

Again the sides of each of these dispensers may be arcuately shaped inwardly toward each other, as indicated at 34, to engage the sides of the tape roll if the roll is, in fact, the proper gauge for width of the sides of the tape dispenser. Such an engagement should be light and permit the easy rotation of the tape roll through the dispenser. However, it provides an additional aid in the smooth, uniform dispensing of the tape from the roll.

I claim:

30 An adhesive tape dispenser comprising a shoe having guides to engage the sides of an adhesive tape roll, a pair of spaced transverse bearing surfaces on the shoe to engage the outer perimetral surface of the roll, an upwardly extending surface on said shoe positioned between said spaced transverse bearing surfaces for receiving the adhesive side of the tape on the roll, a second upwardly extending surface on said shoe in spaced relation to the first extending surface, a transverse lip on said second upwardly extending surface to receive the adhesive side of the tape, and a cutting bar on said lip, the end of the tape when not in use passing off the roll with the adhesive side lying against the first upwardly extending surface and on said lip and bridging therebetween to hold the shoe on the roll and the tape in readiness for dispensing.
